UNITED STATES PATENT OFFICE.

ELISE ANDREWS AND HERBERT P. ANDREWS, OF PORTLAND, OREGON.

HAIR-WAVER.

1,073,014.

Specification of Letters Patent. Patented Sept. 9, 1913.

Application filed May 15, 1912. Serial No. 697,473.

To all whom it may concern:

Be it known that we, ELISE ANDREWS and HERBERT P. ANDREWS, citizens of the United States, residing in the city of Portland, county of Multnomah, and State of Oregon, have invented certain new and useful Improvements in Hair-Wavers, of which the following is a specification.

Our invention relates to hair wavers, and more particularly to a device by means of which hair can be made wavy without being wrapped or twisted around curling irons or other curling devices such as are in common use.

Among the salient objects of our invention are, to provide a new and improved device for forming in the hair a series of waves or crimps, whereby to make it as nearly as possible like hair which is naturally so; to provide a device of the character referred to which is more conveniently applied to the hair and which is less injurious thereto than are the old style curling irons; to provide a device of the character referred to comprising companion pressing or molding members between which the hair can be placed and pressed as said members are closed together, the hair being held and pressed or molded into waves or curls when the device is heated; to provide in combination with companion members adapted to so receive and press the hair therebetween, a series of holding combs adapted to be moved alternately in opposite directions laterally of said companion members, whereby to move portions of the hair placed therebetween to one side, and other alternate portions thereof to the opposite side, thus forming and holding it in curved lines extending back and forth from one side to the other, for the pressing and molding operation; to provide in combination with companion pressing and molding members, a heating medium therein for heating the hair to the right temperature to cause it to set in the form in which it is held; and, in general, to provide an improved and simplified device of the character referred to, comprising companion members adapted to be clamped together, with means in combination therewith for forming and holding the hair, placed therebetween, in waves or curves for the treating process.

In order that others may understand our invention, we have shown in the accompanying sheet of drawings, for purposes of illus-

tration only, one practical embodiment thereof, which we will now describe.

Figure 1 is a side or edge elevation thereof, partly in section, showing the corrugated or wave-like forms of the companion members, with hair placed therebetween; Fig. 2 is a face or plan view of one of the companion members, being the one to the left of Fig. 1, with a small amount of hair laid thereupon, and with a series of combs set down thereupon, in their respective slots, to show how portions of the hair can be moved to one side, or in one direction, and alternate portions thereof moved in the opposite direction; and Fig. 3 is a cross sectional view taken on line 3—3 of Fig. 1 indicating also resistance coils for electrically heating the device.

In this illustrative embodiment of the invention, the companion pressing members are designated as 1 and 2 and are provided with corrugated or wave-like meeting faces adapted to interfit with each other and to receive hair therebetween, in the manner indicated in Fig. 1. These members are preferably formed hollow and as light as possible, and to have therein a series of heating coils, as 3—3, for heating the pressing or molding faces thereof.

The device can be connected to any suitable source of electric energy, and any of the well known electrical appliances used for regulating and controlling the temperature of the device, or for admitting or cutting off the flow of current thereto.

When the hair is pressed between the members 1 and 2, it is thereby formed into waves or crimps, and when current is turned on and the members are properly heated, the hair is thus set. It is to be understood, of course, that any of the known powders or other preparations can be used in the pressing operation for giving permanency or staying quality thereto. We have also provided another means for forming the hair into curves or crimps extending back and forth, from side to side, and when this means is applied to the form of device shown in the drawings, these curves or crimps stand in oblique planes, as distinguished from a vertical or horizontal plane. In order to form these curves extending from side to side, we provide the companion pressing members, of whatever form they may be, upon their meeting faces with a series of sliding combs, as 4—4, adapted to be moved laterally in opposite directions in slots or slideways 5 and

6, in the members 1 and 2, respectively. In the form shown in the drawings, the combs are slidably mounted in oppositely disposed slots formed in the crests and troughs of the 5 meeting faces of the wave-like forms, so that if said combs are moved laterally alternately in opposite directions, the portions of the hair passing over the crests of either of said wave-like forms are moved to one side or in 10 one direction, and those portions of the hair passing across the troughs of the same form are moved in the opposite direction, so that there is a double formation or curvature given to the hair in the form of device here 15 shown and described. It is curved or waved up and down, and is also curved from side to side, in an oblique direction from crest to trough.

It will thus be understood that we have a 20 device providing two ways of forming waves or curls in hair placed therebetween, and that devices can be constructed for using both methods separately, or a device similar to the one here shown and described can be 25 made where both methods are used in one machine.

We are aware that changes can be made in the embodiment here shown for illustrative purposes without departing from the 30 spirit of the invention, and we do not, therefore, limit the invention to the form shown, except as we may be limited by the hereto appended claims.

We claim:

35 1. In a hair waver, in combination, companion members having opposed pressing surfaces adapted to fit together and to re-

ceive hair therebetween and provided in their adjacent faces with registering transversely extending slots or guideways, and a 40 series of combs slidably mounted in said slots or guideways for moving portions of hair placed therebetween in opposite directions.

2. A hair waver comprising in combination two companion pressing members having interfitting corrugated faces adapted to receive hair therebetween and provided with oppositely disposed transversely extending slots or guideways extending longitudinally 50 of the corrugations in said meeting faces, a series of combs slidably mounted in said slots or guideways, and means within said members for heating the same.

3. A hair waver comprising in combination, companion members, each the counterpart of the other, and having corrugated molding or pressing faces adapted to receive hair therebetween, said members being provided longitudinally of said corrugations 60 with oppositely disposed slots or guideways, a series of combs slidably mounted in said slots or guideways, heating coils within said members for heating the faces thereof, substantially as described.

In witness whereof we have hereunto set our hands this 6th day of May, 1912, at Portland, Oregon.

ELISE ANDREWS.
HERBERT P. ANDREWS.

In presence of—
ALFRED TAYLOR,
DANIEL E. POWERS.
